UNITED STATES PATENT OFFICE.

ANTHONY PATTERSON, OF CARDIFF, ENGLAND.

VALVE FOR HYDRAULIC ENGINES OR MACHINERY.

SPECIFICATION forming part of Letters Patent No. 738,730, dated September 8, 1903.

Original application filed May 13, 1902, Serial No. 107,175. Divided and this application filed March 30, 1903. Serial No. 150,298. (No model.)

To all whom it may concern:

Be it known that I, ANTHONY PATTERSON, a subject of the King of Great Britain, residing at Cardiff, in the county of Glamorgan, Wales, England, have invented certain new and useful Improvements in Valves for Hydraulic Engines and Machinery, (Case B;) and I do hereby declare the following to be a full, clear, and exact description of the invention, such as will enable others skilled in the art to which it appertains to make and use the same.

My invention relates to valves for hydraulic engines and for hydraulic machinery. By my improvements such valves are of increased efficiency because they are more completely water-tight. They are more thoroughly balanced, and hence the wear and tear in them is reduced, and they are actuated with greater ease and expedition and are under more complete control. They are suitable for very high water-pressure. The valves are less liable to shocks and consequent injury to themselves and the engines or machines in connection with which they are fitted and in the operation of which they are employed.

This application is a division of my former application, Serial No. 107,175, filed May 13, 1902.

In the accompanying drawings, Figure 1 is a longitudinal central section of a valve constructed in accordance with my invention. This form of valve is a double starting or regulating valve for use in connection with reversing-engines or with a hydraulic cylinder to both sides of the piston of which water is admitted or with coupled rams and in similar cases. Fig. 2 is a longitudinal central section taken at right angles to the section shown in Fig. 1. Fig. 3 is a vertical cross-section of the same on the line E F of Fig. 1, and Fig. 4 is a vertical section on the line G H of Fig. 2.

The valve has two throats *b* and *c*, which extend in opposite directions from the conical center piece *a*, being made integrally therewith. These throats are hollow, and the ends thereof are closed by plugs *w*, which are inserted after casting to fill apertures left for convenience in casting.

At the outer end of the throat *b* is a coupling-box *d*, through which the inlet-pipe *d'*

enters, which inlet-pipe is arranged at right angles to the axis of the throat *b*.

The coupling-box is provided with stuffing-boxes held in position by bolts 1. A similar coupling-box is fitted on the outer end of the throat *c*, at which point a stuffing-box is also provided held in place by the bolts 2. By branches extending from the coupling-boxes the water supply and discharge pipes are connected to the valve at right angles to the axis thereof. The disposition of the supply and exhaust apertures at right angles to the axis of the valve causes a reduction of the shock.

The throats *b* and *c* are united by the center piece *a*, made integrally therewith. This center piece is conical in shape to facilitate the easy assemblage of the parts. In this center piece are three water-passages *f*, *g*, and *h*, the passage *f* being approximately in the center of the center piece *a*, as shown in Fig. 3. This passage has a port *f'* at one end thereof and a port *f''* at the other end. The passage *g* has a port *g'* and the passage *h* has a port *h'*.

The center piece *a* is surrounded by a casing *i*, also made conical, which has branches *i'* and *i''*, by which communication is established with the engine.

In the casing *i* are two water-passages *j* and *k*. The passage *j* has two ports *j'* and *j''*, and the passage *k* has two ports *k'* and *k''*.

The valve is fitted with stuffing-boxes *l*, in which there are compressible or yielding packings, such as hemp packing or the like, and by the use of the stuffing-box thus packed the valve can be kept water-tight by tightening up the gland, which can be done with great nicety. Bolts 3 4 unite the central valve-casing with the coupling-boxes located at either end of the valve.

n represents the lever for stopping, starting, and reversing the engine. It works over a segment 5, having end pieces 6 and 7 and a slot 8. A pin 9 slides in a guide 10 on said lever, and the handle 11, pivoted to said pin and said lever, serves to draw it away from the segment when it is desired to shift the valve.

A spring 12, attached to the handle 11, normally holds the pin 10 down against the

segment 5 or in the slot 8 thereof. The valve has a lap, as is shown at a' in Fig. 3.

The lever n is provided with arms 13 14, which are splined to the throats b and c of the valve, and screws 15 16 serve to fasten these arms to the throats of the valve. The throat c does not extend through the outer end of the coupling-box e . This throat is always the water-exhaust throat, and the throat b is always the water-supply throat, and this condition does not alter with the changes in the direction in which the engine is running.

Having thus described my invention, what I claim as new, and desire to secure by Letters Patent of the United States, is—

1. A double-acting starting or regulating valve for use in connection with reversing-engines, consisting of a center piece having two long throats secured thereto, said center piece being provided with three passages, in combination with a casing surrounding said center piece and provided with passages and ports, supply and exhaust pipes connected at the ends of the valve respectively and located at right angles thereto, means for moving said valve and coupling-boxes independent of the central casing and receiving the ends of the supply and exhaust pipes, substantially as described.

2. A double-acting starting or reversing valve for use in connection with hydraulic engines, consisting of a conical center piece provided with three water-passages, long hol-

low throats connected with said center piece, in combination with a conical casing, provided with passages and ports, surrounding said center piece, supply and exhaust pipes connected at the ends of said valve at right angles thereto, a hand-lever for operating said valve, means for retaining said hand-lever in position and coupling-boxes independent of the central casing and receiving the ends of the supply and exhaust pipes, substantially as described.

3. A double-acting starting or regulating valve for use in connection with hydraulic engines, consisting of a conical center piece provided with three passages, two long throats oppositely arranged connected to said center piece in combination with a conical casing provided with passages and ports surrounding said center piece, supply and exhaust pipes connected at the ends of said valve at right angles to its axis, stuffing-boxes, a hand-lever for operating said valve, said hand-lever being provided with branches connected to the two throats of said valve, means for holding said valve in position, and means for securing the parts together, substantially as described.

In testimony whereof I affix my signature in presence of two witnesses.

ANTHONY PATTERSON.
